UNITED STATES PATENT OFFICE.

ARTEMAS W. FISHER, OF SOUTH BEND, INDIANA.

CARBURETER.

1,319,522.

Specification of Letters Patent. Patented Oct. 21, 1919.

Application filed May 22, 1914, Serial No. 840,263. Renewed March 27, 1919. Serial No. 285,640.

To all whom it may concern:

Be it known that I, ARTEMAS W. FISHER, a citizen of the United States, residing at South Bend, in the county of St. Joseph and State of Indiana, have invented certain new and useful Improvements in Carbureters, of which the following is a specification.

My invention relates to improvements in carbureters more especially intended for the carburation of hydro-carbon commonly known as petroleum or paraffin though adaptable also to ordinary gasoline. Some of the special features of my improvements comprise means which enable me to maintain great differences of temperature between the fuel and the air which is used to atomize it and also combine therewith simultaneously to form an explosive mixture; means for inclosing the fuel in successive varying cones of air; means for insulating the fuel delivery parts from the rest of the metallic structure to conserve the heat of the air and also keep the fuel cool; means for admitting supplemental air to the fuel mixture and automatically controlling the same; means for supplying the heated air at a temperature to not exceed the ignition point of the mixture; and means for coordinating the movement of the throttle with the fuel valve and the primary and secondary air supply, thereby controlling the relation of fuel to load, air to load, and the combined mixture to the varying needs of practical operation.

With these and other ends in view I illustrate in the accompanying drawings such adaptations of the improvements as disclose the fundamental features thereof without limiting myself to the specific details shown.

Figure 1 shows a diagrammatic side elevation of associated parts.

Fig. 2 shows a side elevation partly in section.

Fig. 3 is an enlarged side elevation in section disclosing internal parts in their co-operating relation, also showing the throttle control which is further illustrated in Fig. 5.

Fig. 4 is a detail elevation of the connections from the eccentric on the throttle shaft to the fuel valve.

Fig. 5 is an elevation similar to Fig. 4 showing the structure disclosed in Fig. 3 which is a modification of the parts illustrated in Fig. 4.

Fig. 6 is a plan view of Fig. 1.

Fig. 7 illustrates a means for holding the air valve inactive.

A suitable base 1, supports the commingling hood 2, an automatic control 3 for the modifying air, a fuel chamber 4, a valve casing 5 and primary inlet parts 6. Hood 2 and air control casing 3 are easily removable from base 1. The parts 4 and 5 are instances as being cast integrally with 1, but this is immaterial as any means for suitably supporting these parts in operative relation will serve.

The commingling hood 2 has an outlet 7 in which the throttle 8 is placed. This outlet leads to the intake manifold of an engine while the exhaust manifold may supply heated air by means of any desired baffle chamber or labyrinthian passages as diagramed in Fig. 1, at 9, to supply highly heated air to air intake 6. The temperature is maintained as high as possible, not exceeding the ignition point of the charge. If found desirable I may supplement the hot air supply from 9 by a suitable compressor shown in Fig. 1 adapted to coöperate therewith or substitute that source as may be found advantageous.

The fuel is admitted to chamber 4 through inlets 10 and 11. These are supplied with suitable valves which are inter-connected by means of any desired link and crank parts or other mechanism. The purpose of this is to enable the operator to use gasoline only in starting the engine, to shift to oil alone, to change to varying proportions of oil and gasoline combined, or to shut off both inlets completely, all being accomplished through the variable throw of a control lever 12. A suitable link may reach to the operator's position. In order to enable him to know by sense of touch or sound as to whether the position reached by the arm 12 is the desired one, a suitable well known form of segment with spring detent may be connected therewith.

Arm 12 may be a continuation of a short arm 13 which connects with arm 15 by means of a link 14. The oil valve 16 leads to inlet 10 and valve 17 to gasoline inlet 11. The three main positions are shown on valve 17 by letters "G", "B" and "O", signifying respectively "gasoline", "both" and "oil". A fourth position, designated by "C" is the position wherein both valves are closed.

The fuel supply is controlled by means of

5 a valve in its caging held in the cast portion 5. This is interconnected with the throttle shaft 18 so as to coordinate the fuel flow with the delivery of the explosive charges to the engine. The throttle shaft 18 is operated by an arm 19 under control of a suitable link or rod 20. A limit stop 21 may be cast alongside of the outlet 7 and a set screw 22 placed in arm 19 co-operating therewith to limit the closure of the throttle to the point of just keeping the engine running without risk of "killing" it.

10 The throttle shaft 18 may be interconnected with the fuel valve 26 as follows. An eccentric 23 is attached to stem 18 on the outside of the casing. It is shown by dotted lines in Fig. 2. A projection is formed on the eccentric into which a threaded stem 24 is placed and a locking thumb nut engaging the threads of the stem and the face of the projection securely holds it in any position to which it has been adjusted. The stem 24 may be easily adjusted in the distance it projects from the eccentric 23 by using a 15 knurled thumb disk 25 fastened to it to thread it a greater or less distance into the eccentric. The disk 25 may project below the end of the stem 24, so as to form a seat within itself into which stem 26 may project. The purpose of the "seat" shown in dotted lines of Fig. 1 is to hold stems 24 and 26 in working relation to each other. The valve 26 may be kept from entirely closing by raising the stem 24 in the eccentric 20 to such a point that when the eccentric is in its lowest position the stem 26 will not be fully seated thus admitting enough fuel to prevent killing the engine. This valve has threaded thereon a spring adjustment 25 27 which slides in the valve cage 28. By means of this caging the entire valve, its detachable seat 29, etc., can be removed from the cast projection 5, thus making all 30 of the parts easily accessible and insuring economy of construction as well as standardization and interchangeability of parts.

35 The cage 28 threads into 5 for a short distance. It has a beveled sealing portion 30, a fuel aperture 31 and an outlet therefrom. The sealing of 30 is so arranged that when this takes place the fuel duct 67 will register with the fuel passage of the removable seat 29 and the aperture 31 with the "cast in" opening 32 leading from the fuel chamber 4. In case of any damage accruing to the seat 29 through grit, etc., it can be replaced by removing follower nut 33 from the under side of the casting and unscrewing 29 from the cage 28. A head formed on 40 29 insures the fuel passage coming into proper alignment with the companion outlets. A spring 34 abuts against a shoulder within 28 and engages adjusting sleeve 27 whereby its tension may be varied. The 45 lower end of the valve 26 is carefully ta-

pered so as to very gradually open the fuel passage of 29. The stem 26 near its upper end may be slightly larger in diameter to accommodate a thread for follower sleeve 27 which is free to slide up and down in cage 28. The counter bored opening in 28 for 50 27 extends to about midway of its length. Any well known form of coil spring 34 is placed in such opening so as to loosely encircle stem 26 and abut on the under side of 27. As 27 is rotatable on the threaded part of 26 the tension of spring 34 may be varied.

55 The valve stem 26 may also be kept from entirely closing the fuel supply whereby just enough fuel will be admitted to keep the engine turning over by using an annular beveled disk 35 secured to the stem and causing its beveled edge to engage an adjustable limit screw 36 having a corresponding cone end. With such an arrangement an elastic compressible connection may be desired between the stem 26 and the throttle shaft 18. This is effected by making a separate stem 37 slidable in two ears and carrying therebetween an annular table collar 38. 60 The shaft 18 is provided with a collar 39 carrying a small crank pin 40. A stiff spring 41 completes the connection and suitable "pillar" ends are used in forming seats therefor so as to insure its not becoming displaced.

65 The "pillar" ends are formed by reducing the diameter of the lower end of stem 37 so as to form a shoulder for spring 41 to abut against. The upper end of stem 26 is similarly reduced in diameter and for the same purpose. If desired a small shouldered collar 38 may be placed loosely between the spring 41 and stem 26 as shown in Fig. 5. In this adaptation the crank pin 40 instead 70 of eccentric 23 serves to actuate valve stem 26.

75 As shown valve stem 26 operates in a cage 28 whose seat 29 may be replaced for any desired purpose. Of course it is obvious 80 that the valve 26 could be made to seat directly in part 5 without the use of 29, hence I do not limit myself to the use of the cage and its removable seat.

85 The fuel chamber 4 contains a float 42 which rides by means of an elastic connection 43 on the ball valve stem 44 which passes through a tube 45 that is threaded into the removable valve nipple 46. A suitable seat for the ball 47 is provided and fuel outlets therefrom are also formed therein. The stem 44 and attached ball are held in a raised position by a suitable coil spring 48. As the fuel supply reaches the level of the outlet of conical slit 79 the float 42 rises, 90 being followed by the stem 44 and ball 47 thus shutting off the supply until such time as enough fuel has been consumed to drop the float, when the spring 43 will press stem 44 and ball 47 downward and admit a new 95

supply of fuel. By removing inlet plug 11 all of these parts but the float can be removed intact. A suitable cover incloses the chamber. The spring 43 prevents the float 5 acquiring periodic movements known as "hunting."

The supplemental or secondary air intake through 3 is effected by forming a suitable passage 49 within the base 1 which leads 10 into a chamber 50 above the valve 51 and among other purposes is used to reduce the consumption of fuel. After the engine has come to its lower range of speed in starting under load as the inertia of the load is overcome the engine will of course accelerate causing the auxiliary air port to be uncovered to admit air to the mixture, the amount of this dilution being dependent on the extent to which the air openings are uncovered. In this way the normal air passing through inlet 6 will be modified according to the speed of the engine, racing will be prevented and fuel saved. The casing 3 screws into 1 and it has openings 52 formed 20 therein. A bottom 52^a is threaded onto 3 and a central tube 53 is fastened therein. This tube forms a guide for the valve 51 and the tension spring 54 which rests in a cupped recess of the valve. A valve 80 is 30 placed at the upper end of this tube and it has a hole formed at its lower end. A suitable adjusting sleeve 55 makes it possible to change the spring tension. Openings 52 are controlled by a piston 56 which is carried 40 by the valve 51. A "counter weight" spring 57 placed beneath the piston compensates for the weight of the movable parts.

The supplementary air intake through the casing 3 may be made inactive when the engine is starting so as to insure a rich fuel mixture at this period and also thereafter automatically dilute the strength of the same when the engine is running at speed. When the valve 80 is closed the piston 56 45 will be prevented from being freely raised on account of the vacuum formed beneath it, and the compression of spring 54, thus permitting the suction of the engine to but slightly open valve 51 and in consequence 50 the fuel charge will be but slightly diluted. The extent of this action may be entirely 55 stopped by hook 83. The valve 80 may be opened and closed in any manner after the engine has come to speed. It controls the 60 passage of air through the tube 53 and opening 89 shown in Figs. 2 and 7 into the vacuum space beneath piston 56. The running position of piston 56 if hook 83 is not used 65 and valve 80 is not closed is determined by the suction of the engine and the opposing 70 compression of spring 54. The greater the suction the more valve 51 will tend to open and further dilute the fuel charges. However there comes a time when the spring 54 75 will prevent a further dilution and the mix-

ture may be said to have reached standard proportions for the running conditions then existing.

The hot air supply 6 may terminate in a cone 58, through which any desired number 70 of fuel perforations are formed. The conical deflecting head 59 threads into perforated centers placed within the tube 6. To retain concentric parallelism between head 59 and cone 58 and form the annular conical 75 slit 79 a suitable number of distance pieces 60 may pass diagonally into the conical slit, being adjustably held by a conical screw 61. This screw adjusts all of the pins 60 simultaneously. Suitable large ends formed on 80 the pins prevent their loss should the head 59 be removed for any reason. A gland nut 62 holds tube 6 central. The annular opening 63 may be filled with non-conducting material and the annular chamber 64 surrounding it connected with the air for free circulation, by openings 65, so as to keep the fuel passage way 66 as cool as possible. This passage way leads into duct 67 which connects with valve 26. If desired a separate 90 "priming" inlet 87 may be formed as shown in Fig. 6 in this duct. Insulating material is placed at 68 and 69 forming the first mixing space 78.

A deflecting "cone" 70 surrounds 58. It 95 has openings 71 and an annular flaring extension 72 which rests against a seat within the hood 2. Openings 73 are formed in this part. These lead into the second mixing space. As the hood 2 is screwed down, 70 is 100 securely held on base 1. Openings 74 lead from 49 into annular chamber 75. If deemed desirable the chambers 49 and 64 might be combined and openings 65 substituted. The "cone" 70 flares outward at its top. Directly 105 above it is a deflecting or baffle plate 76 closed at its center and above this is a second plate 77 with a central opening. This plate has an annular flange which just fits inside the hood 2 resting against a suitable ledge 110 in which position it may be riveted to the hood. Plate 76 is supported from 77 by suitable distance pins.

The auxiliary air entering through 3 serves to modify the mixture produced by 115 58 and 59. At low speeds practically all the air is admitted through 6. When the speed is low under heavy load with open throttle and the suction least the spring 54 is but slightly compressed and the valve 51 admits 120 but a small amount of air, thus leaving the mixture rich to combat the load. When the engine is speeding up the suction becomes greater, valve 51 opens more and the speed is controlled because the auxiliary air dilutes 125 the richness of the mixture thereby reducing the force of the explosions. The range of action of valve 51 is controlled by the piston 56, which under excessive demands shuts off openings 52 more or less. If desired any 130

suitable mechanical locking device as shown in Fig. 7 may be used to hold valve 51 inoperative until a working speed has been reached. This may comprise a lever 81 hinged at 82, on an ear projecting from the cap 52*. It is provided with a hook end 83 that enters an air opening 52 and is adapted to pass above the rim of valve 56 so as to hold it and valve 51 inactive as long as desired. A spring 84 normally holds the hook 83 in its inoperative position until link 85 attached to lever end 86 is pulled by the operator. The ear for pivot 82 might equally well project from casing 3. Any kind of "tickler" may be employed with the float 42 so as to flood the chamber 78 through the annular conical slit 79 when the carburetor is used with ordinary gasoline. If petroleum is the fuel employed, such priming would obviously be accomplished by the interconnected system of valves shown in Fig. 1 or by the use of any well known three-way valve placed on the dash within reach of the operator.

When the hot air is above the boiling temperature of the oil a mechanically fixed gas is instantly produced, not giving time for carbon products to form thus eliminating the condensation of fuel at any point. The thorough atomization of the fuel and its simultaneous vaporization produces a homogeneous mixture that avoids premature explosions, through the absence of "lumpy" charges.

In using heavy fuels it should be remembered that the more volatile portions are combined with those less easily vaporized. If the fuel is heated before atomization takes place these highly volatile portions quickly vaporize and the particles which only respond to higher ranges of temperature are left to encumber the fuel passages, cylinders and pistons with deposits of precipitated carbon.

When an engine is running on smallest load and lowest speed with a substantially "closed" throttle, its compression is the least and it is kept in operation by a small volume of a hot and rich mixture which insures certain ignition. With the throttle opened more, a larger volume of the mixture will flow to the engine. This is regulated by the coördinate action of fuel valve 26, in combination with air admitted through openings 71 and 73, the temperature and richness of the charge being reduced proportionately to the quantity of cold air admitted. The device 3 insures the maintenance of a constant fuel suction independent of the throttle position and the volume of the mixture delivered to the engine.

The higher the temperature of the air entering 6 the smaller the amount that will be required. The temperature will drop if the power demand is excessive, through the in-

crease in volume. The fixed gas generated, without the aid of a separate gas producer, by exceptionally hot air is of such a quality as to permit a larger proportion of air to be mixed with it. The hotter the air (not exceeding the ignition point) the more the quality of the gas will be improved which results in a large increase of fuel efficiency.

What I claim is,

1. A kerosene fuel supply, a suitable duct of small capacity leading therefrom to an annular delivery chamber, fuel passages therefrom opening into an annular air outlet, means for controlling passage through the duct, an air supply, a passage of large capacity leading therefrom to an annular outlet encircled by the delivery chamber and insulated therefrom, means for heating the air, a cooling chamber adjacent the fuel delivery external thereof, and a common outlet for the combined air and fuel.

2. A fuel supply, an air supply, ducts from each to adjacent points, a common delivery for both comprising, means for passing a hollow conical layer of air to a mixing chamber, and a series of fuel delivery openings external of the air cone and opening thereinto, a suitable passage from the fuel duct to such openings, a cooling chamber adjacent the openings, and means for heating the air.

3. A cold fuel supply, a highly heated air supply, means for insulating their outlets from each other, means for combining the hot air and fuel through the velocity and temperature of the air supply and means for modifying the proportions between the air and fuel.

4. A fuel supply, a hot air supply, separate passages for each, a common delivery for both, means comprising a heat insulating barrier placed between said passages so as to prevent the heat of the air from being freely transmitted to the fuel, means for reducing the fuel to an atomized state and simultaneously volatilizing the lighter and heavier particles thereof.

5. A fuel supply, a source of hot air, a cold air supply, separate passages therefrom to a common outlet, a cold air chamber adjacent the outlets for keeping the fuel cold, means for heating the first mentioned air supply, means for combining the heated air and cold fuel comprising a series of fuel outlets arranged external of a conical slit through which the hot air is delivered, a mixing chamber in advance of said outlets and slit, means for admitting cold air to the chamber in conically arranged streams, and automatic means for controlling the volume of such air.

6. A fuel supply, means for delivering the same in a conical stream, an air supply, means for directing it in a diverging conical stream across the fuel, means for deflecting the fuel into an approximately par-

allel course to the air current, means for encircling such mixture by a second body of air, means for subsequently encircling the mixture in a third current of air, and means 5 for automatically varying the second and third air sources.

7. A fuel supply, a source of heated air, means for delivering the same in a continuous thin annular conical stream, suitable 10 means for admitting the fuel into said stream perpendicular thereto and externally thereof, means for controlling the passage of mixed fuel and air coördinately with the supply of fuel to said air, and means for 15 diluting the mixed fuel as needed.

8. An atomizer for carbureters comprising a centrally placed air tube having an out-

wardly flaring end, a conical plug supported by the tube, means for adjusting the same to change the channel formed between the 20 conical parts of the plug and tube, means for positively securing parallelism between the elements of the adjacent faces of the channel, a support for the tube, a fuel passage adjacent to and encircling the cone end 25 of the tube, and openings through the tube connecting the channel with the fuel passage.

In testimony whereof I affix my signature in presence of two witnesses.
